VARIABLE FILAMENT INDUCTOR

Charles James Starner, Haddonfield, N. J., assignor to Radio Corporation of America, a corporation of Delaware

Application September 27, 1951, Serial No. 248,501

11 Claims. (Cl. 315—105)

1

This invention relates to variable inductors, and more particularly to a variable inductor arrangement suitable for use in the filament circuit of a high-power electron discharge device capable of operating over a large frequency range.

Triode amplifiers of the grounded-grid type may be utilized in high-power radio transmitters, particularly when the transmitters are to be operated over a large frequency range. This type of operation requires that the input voltage to the amplifier be applied between cathode and ground. If the amplifier tube is the direct heating filament type, the input inductance is placed in series with the filament power supply leads. In tuning over a large frequency range, it is necessary to vary the inductance. The inductance is usually varied by shorting out a portion of the inductor. However, the variation of the inductance produces a change in the voltage at the filament terminals of the tube due to the alteration of the filament circuit impedance at the filament power frequency. In very high power amplifying tubes, this variation may exceed the manufacturer's ratings for proper operation of the tube.

An object of the present invention, therefore, is to provide means for varying the effective inductance of coils in series with the filament leads of a grounded-grid triode amplifier without changing the filament voltage at the filament terminals of the electron discharge device.

Another object of this invention is to provide in the filament circuit of an electric tube an adjustable inductor circuit for radio frequencies which maintains a constant resistance to the filament heating power supplied therethrough.

A feature of the invention comprises a novel arrangement employing a push-button shorting device for simultaneously varying the inductance of a pair of coils by the same amount.

The invention is hereinafter described, by way of example only, in connection with a grounded-grid triode amplifier capable of operating over a frequency range of from four to twenty-seven megacycles at a high power input. The two filament terminals of the vacuum tube are connected to a filament transformer by means of an inductor in series with each one of the two filament leads. Each inductor is tuned by means of a variable tap connected to one end thereof. A resistor is connected in series with the variable tap of each inductor. These resistors are chosen to have a high impedance to the 60 cycle filament voltage but a low impedance to radio frequency energy, thereby effectively confining the filament heating current to the entire inductor. The re-

sistors may take the form of nichrome ribbons

An advantage of the present invention is that the resistors, in addition to functioning as connecting leads, also operate to dampen undesirable resonances in the shorted portions of the inductors.

Other objects, features and advantages will appear in the subsequent detailed description which is accompanied by a drawing, wherein:

10 Fig. 1 is a schematic diagram illustrating the application of the variable inductor arrangement of the invention to a grounded-grid triode amplifier;

15 Fig. 2 illustrates a side elevational view of the mechanical structure of one of the variable

15 mechanical structure of one of the variable filament inductors shown in Fig. 1, including a push button tuning mechanism; and

Fig. 3 is a top sectional view of Fig. 2 along line 3-3 illustrating the two variable filament inductors and including the resistor ribbons.

Throughout the figures of the drawing the same reference numbers are employed to designate the same components.

Referring to Fig. 1, there is shown a grounded-grid triode amplifier employing an evacuated electron discharge lamp as the source.

electron discharge device 10 having an anode 12, a grid 14, and a filament 16. The filament 16 is coupled to the secondary winding of a transformer 18 by the filament leads 20. The primary winding of transformer 18 is connected to a suit-
30

able alternating current power source 22. In series with the filament leads 20 are identical inductors 24. Each inductor 24 is tuned by a variable tap 26 connected to one end thereof. 35 Two resistors 28 are connected so that one resistor is in series with each of the taps 23. The resistors 28 are chosen to have a high impedance to the alternating current filament voltage but a relatively low impedance to radio frequency

40 energy when compared with the impedance of the inductor 24, thereby each resistor 23 effectively confines the filament heating current to the entire inductor 24. A by-pass capacitor 33 connects each junction of the isolating resistor
45 28 to ground.

An input tuning capacitor 32 is coupled in parallel with the filament inductors by means of two blocking capacitors 34, each connected to a filament lead at the tube side of the inductors, with their remaining ends interconnected and attached to one side of the input tuning capacitor 32 at the junction 36. The other terminal of the input tuning capacitor 32 is grounded. The grid 14 of the electron discharge device 10 is connected to a suitable bias source, not shown by

means of the radio frequency choke 38. The grid is grounded at radio frequencies by a capacitor 39.

The anode 12 is connected to the anode inductor 40 of the anode tank circuit 41. The anode tank circuit 41 includes the series inductor 40, capacitor 42, and capacitor 44. Capacitor 44 is connected to ground and forms part of the resonant output circuit. An anode voltage source, not shown, is coupled to the junction of the inductor 40 and capacitor 42 by means of the radio frequency choke 43. An anode ammeter 46, to indicate anode current, is attached between a tap on the secondary of the filament transformer 18 and ground. The amplifier is driven by an exciter, not shown, over lead 48 coupled to the junction 36. The amplifier is connected to an antenna tuner, not shown, over a lead 50 connected to the junction of capacitors 42 and 44.

The input circuit between the ungrounded terminal of the input tuning capacitor 32 and ground is thus composed of the parallel tunable arrangement including the input tuning capacitor 32 in one leg of the circuit and the unshorted sections of the inductors 24, each in series with its bypass capacitor 30, in parallel, as the other leg. Tuning of the input circuit is accomplished by selecting the proper tap on the variable inductors 24 and varying the input tuning capacitor 32 until resonance at the desired frequency is reached.

Referring to Figs. 2 and 3, since the structure and operation of each variable inductor is similar, only one will be described where convenient. Each inductor 24 is in the form of a helix with spaced turns and is inserted in series with one of the filament leads by means of a connector 52 and the connecting bus 54.

The resistor 28 functions as the connecting lead between a lower terminal 56 on the bottom turn of the inductor 24 and a mounting plate 58. A contact bar 60 extends the length of each inductor 24. The contact bar 60 is positioned in relation to the remaining structure by means of insulators 62, and is electrically connected to the mounting plate 58 by means of the link conductors 64.

The value of inductance in the tuned input circuit is varied by shorting out sections of each inductor 24. This is accomplished by a pair of shorting contacts 66 attached to the end of each depressable insulated push button 68, which is positioned to connect the contact bar 60 to a predetermined turn of the inductor 24 when the appropriate push button is depressed. This is best seen by an inspection of the top sectional view of Fig. 3. Since the inductors 24 are identical and are mounted in juxtaposition to each other, depressing one push button 68 effects a connection of a corresponding turn on each inductor 24 with its associated contact bar 60 to simultaneously vary the inductors by the same amount.

The bypass capacitor 30 (shown in this figure as consisting of a plurality of paralleled capacitors) is connected between the mounting plate 58 and the chassis 70 which is at ground potential. The variable input tuning capacitor 32 is mounted on a supporting plate 72 which is insulated from the chassis 70. One side of the variable input tuning capacitor 32 is directly connected to the chassis 70 through a ground bus bar 74. Each blocking capacitor 34 is mounted between the supporting plate 72 and each filament terminal bar 76 to which the filament leads 20 are attached. The filament terminal bar 76 for each filament lead 20 is supported by an insulating support 78. The blocking capacitors 34 are thus in series with one side of the variable input tuning capacitor 32 and the filament leads 20. The upper end of each inductor 24 is connected to each filament terminal bar 76 by means of a connecting bus 54.

10 The blocking capacitors 34 have a value which gives a low reactance at radio frequencies and a high reactance at the power line frequency (e. g. 60 cycles per second). The bypass capacitors are also of a value which have a low reactance at radio frequencies and a high reactance at the power line frequency.

15 The following is an example of the improvement in amplifier operating conditions which result when the invention is utilized in an actual embodiment. An RCA type 9C25 triode was employed.

20 The filament of this electron tube required approximately 280 amperes at 6 volts. Since the filament current must be supplied through the filament inductors 24, a considerable voltage drop results when the entire length of each of the inductors is used. When the inductors are completely shorted by the shorting contacts 66, there is practically no voltage drop. The voltage difference with the inductors completely shorted or entirely in the circuit is approximately 0.3 volt. Since this voltage drop is in addition to other normal variations of voltage, the tube filament voltage can not be maintained within the manufacturer's ratings.

25 Utilizing the system of the present invention, however, these difficulties may be overcome. Employing the circuit shown above in Fig. 1, the resistors 28 are made in the form of a 6 inch length of nichrome ribbon, $\frac{3}{8}$ inch wide and 20 mils thick. In the improved arrangement, the ratio of resistance of each resistor 28 to the resistance of the corresponding inductor 24 is in the order of 10:1. More exactly, each resistor 28 had a value of .02 ohm and the resistance of each entire inductor 24 was .002 ohm, so that practically all of the 60 cycle filament current is carried by the entire length of the inductor and the variation in filament voltage is reduced by a factor of more than ten.

30 Thus, in accordance with the invention, the inductors in series with the filament supply can be tuned over a very wide range of frequencies and the filament supply voltage still be kept within the range of permissible variation. To accomplish the same degree of improvement utilizing the conventional blocking capacitor type of arrangement instead of the system of this invention would require a plurality of capacitors, the cost of which would be more than 500 times the cost of the resistors in this system. An additional advantage is also realized in the corresponding saving in space requirements and maintenance expense. Furthermore, the insertion of the resistors as shown in the circuit in Fig. 1 is useful as a damping device to prevent unwanted resonances in the shorted portions of the inductors 24, thus reducing harmonic generation. The resistors also substantially reduce the amount of current that the shorting contacts 66 have to carry, since practically no filament heating current flows in the shorting circuit.

35 What is claimed is:

1. An electron discharge device system comprising an electron discharge device having a heating element, means supplying heating cur-

rent to said heating element, an inductor connected between said heating element and said supply means, a variable tap connecting one point of said inductor to a second point on said inductor intermediate its ends, and a resistor of high resistance compared to the resistance of said inductor connected in series with said tap between said first point and said second point.

2. In combination, an electron discharge device having a filament, an energizing source having two terminals, inductors respectively connecting the filament terminals to different terminals of said source, a variable tap connecting one end of each of the inductors to a point on the same inductor intermediate its ends, and a resistor having a relatively high impedance to energy from said source compared to the impedance of the inductor connected respectively between said end of each inductor and its corresponding tap.

3. Apparatus for varying inductance in series with a heating element lead of an electron discharge device comprising an electron discharge device having a heating element, a heating element energizing source, leads connecting the said source to the said heating element, an inductor in series with one of the leads, a variable tap connecting one terminal of the inductor to a point intermediate between its ends, a resistor with a relatively high impedance to energy from said source in comparison with the impedance of the inductor connected in series with the tap and said one terminal, and means for supplying radio frequency energy to the other terminal of said inductor.

4. Apparatus for varying inductance in series with a heating element lead of an electron discharge device comprising an electron discharge device having a heating element, a heating element energizing source, leads connecting the said source to the said heating element, an inductor in series with one of the leads, a variable tap connecting one terminal of the inductor to a point intermediate between its ends, a resistor with a relatively high impedance to energy from said source in comparison with the impedance of the inductor connected in series with the tap and said one terminal, said inductor forming part of a parallel tuned cathode circuit for said device, said tuned cathode circuit including a capacitor arrangement in shunt to said inductor.

5. An electron discharge device system comprising an electron discharge device having a heating element, a source of heating current supply, connection means supplying heating current to said heating element from said source, an inductor in said connection in series between said heating element and said source, a variable tap connecting a terminal of said inductor to a point on said inductor intermediate its ends, and a resistor of high resistance compared to the resistance of said inductor connected in series with said tap between said terminal and said point.

6. Apparatus for varying inductance in series with a heating element lead of an electron discharge device comprising a heating element for said electron discharge device, a heating element energizing source, two leads connecting the energizing source to said heating element, an inductor having two terminals connected in series with one of said leads, a contact plate in juxtaposition to said inductor, an isolating resistor with a relatively high impedance to the heating energy in comparison with the impedance of said inductor, said resistor connected between one terminal of said inductor and said contact plate,

and a plurality of push buttons, each of said push buttons having a shorting contact attached to the end thereof adapted to make simultaneous contact with the contact plate and a predetermined turn of said inductor when the push button corresponding to said turn is depressed.

7. Apparatus for varying inductance in series with a heating element lead of an electron discharge device comprising a heating element for said electron discharge device, a heating element energizing source, two leads connecting the energizing source to said heating element, two inductors each having two terminals and each connected in series with one of said leads, two contact plates, each contact plate being in juxtaposition to one of said inductors, two isolating resistors with a relatively high impedance to the heating energy in comparison with the impedance of said inductors, each of said resistors connected between one terminal of an inductor and its associated said contact plate, and a plurality of push buttons, each of said push buttons having a pair of shorting contacts attached to the end thereof adapted to make simultaneous contact between a predetermined turn of each of said inductors and its associated contact plate when said push button is depressed.

8. Apparatus for varying inductance in series with a heating element lead of an electron discharge device comprising a heating element for said electron discharge device, a heating element energizing source, two leads connecting the energizing source to said heating element, an inductor having two terminals connected in series with each of said leads, two contact plates, each contact plate being in juxtaposition to one of said inductors, two isolating resistors with a relatively high impedance to the heating energy in comparison with the impedance of said inductors, each of said resistors connected between one terminal of an inductor and its associated said contact plate, and a plurality of push buttons, each of said push buttons having a pair of shorting contacts attached to the end thereof adapted to make simultaneous contact between a predetermined turn of each of said inductors and its associated contact plate when said push button is depressed, and means for supplying radio frequency energy to the other terminals of said inductors.

9. In a device for supplying heating current to the filament of an electron discharge device, the combination comprising a heating element for said electron discharge device, a filament transformer having a primary and secondary winding, a source of alternating current connected to the primary winding of said transformer, two leads connecting the secondary winding of said transformer to said filament, an inductor having two terminals connected in series with one of said leads, a contact plate in juxtaposition to said inductor, an isolating resistor with a relatively high impedance to the heating energy in comparison with the impedance of said inductor, said resistor connected between one terminal of said inductor and said contact plate, and a plurality of push buttons, each of said push buttons having a shorting contact attached to the end thereof adapted to make simultaneous contact with the contact plate and a predetermined turn of said inductor when the push button corresponding to said turn is depressed.

10. In a device for supplying heating current to the filament of an electron discharge device, the combination comprising a heating element for

said electron discharge device, a filament transformer having a primary and secondary winding, a source of alternating current connected to the primary winding of said transformer, two leads connecting the secondary winding of said transformer to said filament, two inductors each having two terminals and each connected in series with one of said leads, two contact plates, each contact plate being in juxtaposition to one of said inductors, two isolating resistors with a relatively high impedance to the heating energy in comparison with the impedance of said inductors, each of said resistors connected between one terminal of an inductor and its associated said contact plate, and a plurality of push buttons, each of said push buttons having a pair of shorting contacts attached to the end thereof adapted to make simultaneous contact between a predetermined turn of each of said inductors and its associated contact plate when said push button is depressed.

11. In a device for supplying heating current to the filament of an electron discharge device, the combination comprising a heating element for said electron discharge device, a filament transformer having a primary and secondary

winding, a source of alternating current connected to the primary winding of said transformer, two leads connecting the secondary winding of said transformer to said filament, two inductors each having two terminals and each connected in series with one of said leads, two contact plates, each contact plate being in juxtaposition to one of said inductors, two isolating resistors with a relatively high impedance to the heating energy in comparison with the impedance of said inductors, each of said resistors connected between one terminal of an inductor and its associated said contact plate, and a plurality of push buttons, each of said push buttons having a pair of shorting contacts attached to the end thereof adapted to make simultaneous contact between a predetermined turn of each of said inductors and its associated contact plate when said push button is depressed, said inductors forming part of a parallel tuned cathode circuit for said electron discharge device, said tuned cathode circuit including a capacitor arrangement in shunt to said inductors.
